C. L. STOKES

PACKAGE

Filed Aug. 10, 1923

By

Charles L. Stokes

Attorney

UNITED STATES PATENT OFFICE.

CHARLES LAWRENCE STOKES, OF LOS ANGELES, CALIFORNIA, ASSIGNOR OF ONE-HALF
TO I. H. RICE, OF LOS ANGELES, CALIFORNIA.

PACKAGE.

Application filed August 10, 1923. Serial No. 636,895.

My invention relates to improvements in packages which may be quickly opened and their contents made accessible by pulling on a string.

5 The principal object of my invention is to provide a package for holding cigarettes of such character that the package may be flexibly opened centrally by a string.

Another object of my invention is to provide means for flexibly closing the package automatically whereby the contained cigarettes are not only held in position in the package but are also prevented from being crushed.

15 Referring to the drawings in which like numbers indicate the same parts:—

Fig. 1 is a view showing my improved cigarette package.

Fig. 2 is a view of the flexible opening and 20 containing means used.

Fig. 3 is a view showing the package when flexibly sprung apart.

Fig. 4 is a transverse cross section of the filled package.

25 Fig. 5 is a view showing the creasings applied to the flexible container.

In the manufacture of my package, a sheet of stiff paper, or cardboard, 3 is cut to size and creased at 4, 5, 6, 7 and 8 in order to fold 30 to the required position indicated in Fig. 2, it being noted that the upper and lower ends of 3 are open.

A string, preferably a strong small diameter string such as 2 which may be rendered 35 sharp by treatment with sizing, is attached to the bottom of 3 by passing through a hole therein and knotting the end, or same may be attached to 3 in any other suitable manner.

Crease 6 is not made as deep as creases 4, 40 5, 7 and 8 in order to preserve the flexibility of the back of 3 and in some cases it may be desirable to dispense with crease 6 altogether.

The required number of cigarettes 9 are wrapped in tinfoil 12, the ends of which are 45 turned over so as to just meet, thereby forming a joint which just meets but does not overlap, the joint being arranged to come directly under the opening 10 in 3 when the tinfoil 12 containing cigarettes 9 is slipped 50 into 3.

String 2 is now folded in the joint 10 and 3 is encased in an outer wrapper 1 which has its upper and lower ends turned in for rendering the contents air and moisture proof, 55 the upper end of 1 being turned in and folded

as shown in Fig. 1 so that the end of 2 is folded therewith and projects a certain distance therefrom.

It is to be understood that 1 is comprised of a sheet of paper the ends of which are 60 lapped and sealed with paste, the revenue stamps 11 being applied preferably at the upper end, thereby reinforcing the part contiguous to the end of 2 and 1 may comprise the wrapper containing the brand of the cigarettes and so forth, and is preferably glued to 3.

In order to open the package it is simply held firmly in one hand and 2 pulled quickly back against the resistance offered by 11 and 70 1, whereupon a clean cut is made opening one side and the two ends of 1 and by a slight pressure of the hand holding the package on 4 and 8, the package is opened as shown in Fig. 3 whereby cigarettes 9 may be abstracted.

Upon the release of pressure applied to 4 and 8, the flexibility of 3, owing to its stiffness or rigidity, causes the package to close, thereby preserving the cigarettes from loss 80 or being crushed.

In the ordinary paper packages used for containing cigarettes, the cigarettes rapidly become crushed and disintegrated by carrying the same in a pocket, but by my invention I am now enabled to prevent all this loss and inconvenience while supplying at the same time all the necessary parts for a commercial package.

It is an essential feature of my invention 90 to provide a comparatively stiff container for cigarettes which may be easily split substantially centrally for abstracting the cigarettes, but which will always resume its shape while carrying protection for the cigarettes, the 95 stiffness of the container being of a spring-like nature for which many alternatives suggest themselves.

It should be noted that the tinfoil 12 is so folded around the cigarettes 9 that the ends 100 of 12 will just about meet and consequently when 1 is split by pulling on string 2 it is not necessary to touch tinfoil 12 for abstracting cigarettes 9 therefrom because 12 will open in a manner corresponding to the opening of 10 as already described.

I claim:—

1. As a new article of manufacture, a cigarette package comprising a resilient cardboard container having an open joint extend- 110

ing longitudinally thereof and across the ends substantially centrally thereof, a plurality of cigarettes arranged in said package longitudinally thereof, a tinfoil about 5 said cigarettes, the ends of said tinfoil being arranged to form a joint opposite the joint in said cardboard, a covering about said cardboard, and a string between said covering and cigarettes for severing said covering on three 10 sides opposite the joints in said tinfoil and cardboard.

2. As a new article of manufacture, a cigarette package comprising a container having side and end walls of relatively stiff fibrous material, said container being pro-

vided with one resilient continuous side wall and having an open joint extending longitudinally along the opposite side wall and across the end walls substantially centrally and transversely thereof, said container being adapted to have cigarettes packed therein extending parallel with said walls and at each side of said joint, to cover about said container, and a string between said cover and cigarettes opposite the joint in said container.

Signed at Houston, in the county of Harris and State of Texas, this 21st day of June, A. D. 1923.

CHARLES LAWRENCE STOKES.

CERTIFICATE OF CORRECTION.

Patent No. 1,701,316.

Granted February 5, 1929, to

CHARLES LAWRENCE STOKES.

It is hereby certified that error appears in the printed specification of the above numbered patent requiring correction as follows: Page 2, line 22, claim 2, before the word "walls" insert the word "side" and line 23, for the word "to" read "a"; and that the said Letters Patent should be read with these corrections therein that the same may conform to the record of the case in the Patent Office.

Signed and sealed this 19th day of February, A. D. 1929.

M. J. Moore,
Acting Commissioner of Patents.
